UNITED STATES PATENT OFFICE.

CLEMENT B. BISHOP, OF PHILADELPHIA, PENNSYLVANIA, ASSIGNOR TO
BENONI FRISHMUTH, OF SAME PLACE.

SPECTACLES.

SPECIFICATION forming part of Letters Patent No. 372,954, dated November 8, 1887.

Application filed September 21, 1886. Serial No. 214,130. (No model.)

To all whom it may concern:

Be it known that I, CLEMENT B. BISHOP, a citizen of the United States, residing in Philadelphia, Pennsylvania, have invented certain 5 Improvements in Spectacles and Eyeglasses, of which the following is a specification.

My invention consists of certain improvements in the construction of spectacles, designed more particularly for facilitating and 10 economizing their manufacture.

In the accompanying drawings, Figure 1 is a perspective view of a pair of spectacles, illustrating one of the features of my invention, the temples being broken off. Fig. 2 is a view 15 of a modification. Fig. 3 is an enlarged perspective view illustrating the construction of the end pieces. Fig. 4 is a view illustrating the mode of producing half of one of the end pieces. Fig. 5 is a perspective view, also 20 drawn to an enlarged scale, of the end of one of the temples. Fig. 6 is a sectional view of the same, illustrating its position in the end piece. Fig. 7 illustrates a modification of the same.

25 In the manufacture of spectacles one of the chief elements of expense is the filing which has to be done on the different parts, and more particularly the end pieces, which are attached to the ends of the rims. The punching out of 30 these end pieces leaves sharp corners, which have to be filed down.

It is one of the objects of my invention to so construct the end pieces as to dispense with this filing so far as possible.

35 It is a further object of my invention, in applying it to rolled plated spectacles, to produce an article in which all the exposed parts shall be plated.

Heretofore, so far as I am aware, it has been 40 found impossible to produce plated spectacles without leaving some exposed part without plating, and more particularly the edges of the end pieces to which the temples are connected.

45 I attain these objects—that is, I dispense with the filing of the end pieces, and when making plated work produce end pieces with all the exposed parts plated, by striking these end pieces up with rounded surfaces, as shown 50 in Figs. 1, 2, and 3.

Referring to Figs. 1 and 2, A A are the usual rims of the spectacles, split at one end, a, to which the two halves of the end pieces B are soldered, the two halves of these end pieces being of such a character that they can be 55 united or fastened together by means of a small screw, which thus secures the ends of each rim. I form these end pieces B of two halves, b b', Fig. 3, which I strike up with rounding surfaces by means of a punch and 60 die, as illustrated in Fig. 4, so that when the two are united by means of the screw d, Fig. 3, they form an end piece of a rounded or substantially spherical form. As a general rule, the end piece will be in the shape of a flattened sphere or ovoid; but I do not limit myself to any precise shape, so long as each half is struck up with a rounding surface to avoid 65 corners, which might need filing.

In using plated stock to form the end pieces 70 this method of striking up the halves with rounded surfaces enables me to leave a plating over the entire surface, as will be understood on reference to Fig. 4, where the dark line e indicates the plating. A struck-up end 75 pieces such as described, whether made of steel or of plated stock, can be readily distinguished from one which has been shaped by the old filing process, owing to the appearance given to the article by the shaping-die in striking up 80 the end piece. Such appearance will be best understood by those skilled in the art by the use of the descriptive phrase "struck up." The adjoining flat faces of the two halves of the end pieces are milled out in any desired 85 way or by any desired means for the reception of the flattened ends of the temples, or the necessary recesses may be formed in the two halves of the end pieces in the punching operation.

90 For economy and convenience in construction of the spectacles, I prefer to use the same end pieces which unite the ends of the rims for the connection of the temples, so that the use of a separate screw in addition to the securing-screw is obviated. A double end piece may, however, be provided, if desired, as illustrated in the modification, Fig. 2, both end pieces, however, being struck up of a rounding form, as above described.

the optical industry. In order to get a sufficient frictional contact between the flattened end of the temple and the two halves of the end piece, I split the flattened end *e* of the temple *E* at an angle, as illustrated in Fig. 5, and bend the two split ends slightly apart, so as to form a species of spring, which, when the temple end is inserted between the ends *b* and *b'*, is compressed by the latter.

To form a stop to prevent the temple *E* from being turned beyond the position at right angles to the glasses, the milled-out portion of one or both of the half end pieces, *b* *b'*, may, as shown in Fig. 3, be provided with a straight portion, *f*, against which the corresponding straight portion on the eye *e* of the temple bears when turned out to the position at right angles to said glasses, as illustrated in Fig. 6; or corresponding shoulders *f'* may be formed on the end piece or pieces and the eye of the temple, as illustrated in Fig. 7.

Eyeglasses have heretofore been made with rounded end pieces on the rims; but, so far as I am aware, in all such cases such rounding

has been produced by the tedious filing process solely for the purpose of neater finish in the more expensive grades of these eyeglasses. In my spectacles and eyeglasses the end pieces are punched up in a rounding form, and this punching up of the end pieces in rounding form has the specific mechanical purpose of thereby dispensing with the expensive and tedious filing heretofore necessary.

I claim as my invention—

1. A spectacel-²⁵ rim having end pieces with struck-up rounded surfaces, substantially and for the purpose described.

2. The combination of the end pieces of a pair of spectacles with temples having eyes ³⁵ *e*, split substantially as described.

In testimony whereof I have signed my name to this specification in the presence of two ⁴⁰ subscribing witnesses.

CLEMENT B. BISHOP.
